METHOD OF FORMING EXPANDED SHEET METAL.

1,195,221.

Specification of Letters Patent. Patented Aug. 22, 1916.

Application filed January 6, 1912. Serial No. 669,880.

To all whom it may concern:

Be it known that I, HENRY C. HERR, a citizen of the United States of America, residing at Pittsburgh, in the county of Allegheny and State of Pennsylvania, have invented certain new and useful Improvements in Methods of Forming Expanded Sheet Metal, of which the following is a specification, reference being had therein to the accompanying drawings.

The invention relates to manufacture of expanded sheet metal and consists in the method of producing the same.

In the drawings, Fig. 1 is a plan view of the sheet metal blank after the first slitting operation; Fig. 2 is a similar view after a subsequent slitting operation; Fig. 3 is a diagrammatic plan view illustrating the manner of expanding the slitted sheet; Fig. 4 is a diagrammatic longitudinal section thereof; and Fig. 5 is a plan of the product.

It is the special object of the invention to obtain an expanded metal sheet having certain novel characteristics and which adapt it for special uses. The specific use for which the product is designed is the reinforcement of paper or fiber stock used in the manufacture of tubular bodies for barrels and other packages; but it is obvious that there are various other uses for which such a product is equally well adapted.

One characteristic feature of my improved product is that the expanded portions lie in the same plane instead of being bent or twisted as is usual. This adapts the material for insertion between piles of the paper or fiber stock without materially increasing the thickness thereof.

Another characteristic of the material is the combination of expanded and unexpanded portions in the same integral sheet and in the same plane. Such material when used as a reinforcement between plies of a fiber stock has the advantage of reinforcing certain portions of the area to a greater extent than other portions and in the formation of tubular bodies strengthening bands may be formed of the unexpanded portions.

Still another feature of the invention is the novel means of expanding the sheet which avoids the buckling or crimping of the unexpanded portions by reason of the transverse expansion of other portions.

The first step in the process is the slitting

of the sheet so as to form transversely bonded strands with the bonds of adjacent pairs of strands staggered in relation to each other. This step I preferably perform in two operations, the first being the slitting of the sheet such as A, Fig. 1 with the bonds B which interrupt the longitudinal continuity of the slits C in transverse alignment. In the second operation, interrupted slits D are formed intermediate the slits C and with their bonds E centrally between the bonds B. Thus the continuity of the transverse bonds is broken and only the adjacent pairs of strands are bonded.

In the slitting of the sheet A certain portions thereof, preferably the opposite margins F and G are uncut and form longitudinal continuous bands. These bands or unslit portions remain of unaltered length during the subsequent expanding operation of the sheet but they are separated from each other due to the lateral enlargement of the expanded portion. It is therefore necessary to expand the sheet in such a manner that the longitudinal contraction incident to the lateral extension is prevented. This is accomplished by the longitudinal drawing or elongation of the strands during the lateral expansion of the sheet, the amount of such elongation being sufficient to compensate for the contracting effect of bending the strands into oblique angling positions.

In my improved process I preferably obtain the desired effect by the alternate drawing or elongating of the strands and the transverse expansion of the sheet. Thus as shown in Fig. 3 the slitting of the sheet is performed in its two operations successively by slitting rolls II and I and as an incidence to their operation the strands intermediate slits are slightly elongated. The opposite sides of the sheet are then engaged by clamps such as J and are drawn laterally in opposite directions as by means of divergent chains K to which said clamps are attached. The result is the lateral expansion of the sheet a sufficient amount to compensate for the elongation of the strands, while the marginal bands F and G remain unaltered in length.

If the lateral expansion were to be continued without further elongation of the strands it would result in buckling up the

marginal bands F and G and therefore, before further lateral expansion the strands are elongated preferably by rolling between drawing rolls L. The lateral expansion is then continued and will take up the elongation produced by the rolls L until a second pair of rolls L' engage the strands and further elongate the same. This alternate operation of elongating the strands and laterally expanding the sheet is continued until the desired degree of expansion is obtained. The sheet then passes under rolls M which engage the marginal bands F as well as the intermediate portions and seat the sheet with all portions in the same plane.

It is obvious that any number of unslotted portions may be left in the sheet by suitable provision for expanding only the intermediate slotted portions.

What I claim as my invention is:

1. The method of expanding sheet metal, which consists in laterally expanding the sheet, and elongating the strands thereof successively through a series of operations to maintain a constant length of sheet.

2. The method of expanding sheet metal, which consists in laterally drawing the edges of the stranded section apart, and elongating the strands successively through a series of operations to maintain a constant length of sheet.

3. The method of expanding sheet metal, which consists in forming adjacent stranded and unaltered portions successively through a series of gradual operations, in elongating the stranded portion, and in separating the opposite edges thereof to laterally expand said portion and to maintain the longitudinal dimension thereof the same as the unaltered portion.

4. The method of expanding metal, which consists in forming the sheet with alternate

stranded and unaltered parallel portions, and in successively through a series of gradual operations laterally separating said unaltered portions and longitudinally expanding said stranded portions to maintain a constant length of sheet. 45

5. The method of expanding sheet metal, which consists in forming a sheet with a central stranded portion and parallel marginal unaltered portions, and successively through a series of gradual operations in drawing said marginal portions laterally apart and elongating said stranded portion to maintain a constant length of sheet. 55

6. The method of expanding metal, which consists in forming the sheet with adjacent, stranded and unaltered portions, in successively through a series of gradual operations laterally separating said unaltered portion, and longitudinally extending said stranded portion independently of the unaltered portion to maintain a constant 60 length of sheet.

7. The method of expanding sheet metal having a stranded portion of a sheet intermediate unstranded portions, which consists in a series of successive operations upon the 70 stranded and unstranded portions respectively for elongating the stranded portion and separating the unstranded portions thereof.

8. The method of expanding sheet metal, which consists in simultaneously laterally expanding and longitudinally feeding said sheet, and successively elongating the strands thereof to maintain a constant 75 length of sheet.

In testimony whereof I affix my signature in presence of two witnesses.

HENRY C. HERR.
